RELEASEABLE MANUAL CONTROL

Calhoun Norton and Philip O. Hooker, Chicago,
Ill., assignors to Arens Controls, Inc., Chicago,
Ill., a corporation of Illinois

Application August 4, 1945, Serial No. 608,980

15 Claims. (Cl. 74—503)

1

This invention relates to control mechanisms, and particularly to control mechanisms of the manually actuated type, adapted for push-pull movements, and to be locked in various positions of longitudinal adjustment by means of a predetermined rotational movement of the manual control handle.

It is an object of the invention to provide a control mechanism, of the type defined, of improved construction and improved operating characteristics.

More particularly stated, it is an object of the invention to provide an improved control mechanism of the type defined, which may be more readily fabricated and assembled, which is smooth and free in its longitudinal movements, which provides a positive lock when moved to locking position, and which may be more readily adjusted to locked and unlocked condition.

A further object of the invention is to provide an improved control mechanism of the type defined, wherein a positive locking thereof is insured, when desired, regardless of severe operating conditions or factors to which the mechanism may be subjected such, for example, as vibration, moisture, dirt, or other foreign matter, et cetera.

A still further object of the invention, in certain embodiments thereof, is to provide an improved control mechanism, of the type defined, wherein the locking action is effected only upon rotation of the manual control handle in a predetermined rotational direction.

Various other objects, advantages and features of the invention will be apparent from the following specification, when taken in connection with the accompanying drawings, wherein certain preferred embodiments are set forth for purposes of illustration.

In the drawings, wherein like reference numerals refer to like parts throughout:

Fig. 1 is a general assembly view of a control installation incorporating a control mechanism constructed in accordance with and embodying the principles of the invention;

Fig. 2 is a longitudinal sectional view, on an enlarged scale, of the control mechanism of Fig. 1;

Fig. 3 is a transverse vertical sectional view, on a further enlarged scale, of the structure of Fig. 2, and taken as indicated by the line 3—3 thereof;

Fig. 4 is a view similar to Fig. 3, but showing the parts in locked condition;

Fig. 5 is an exploded view of certain parts of the control mechanism illustrated in Figs. 1-4;

2

Fig. 6 is a view similar to Fig. 3, but illustrating a modified embodiment of the invention;

Fig. 7 is a view also similar to Fig. 3, but illustrating a further modified embodiment;

5 Fig. 8 is a partial longitudinal sectional view of a control mechanism, generally similar to that illustrated in Figs. 1-5, but incorporating certain additional structural elements;

10 Fig. 9 is a transverse sectional view of the structure of Fig. 8, on the line 9—9 thereof;

Fig. 10 is a view of the parts shown in Fig. 9, in released or unlocked position;

15 Fig. 11 is a view similar to Fig. 8, but showing a still further structural embodiment of the invention;

Fig. 12 is a transverse sectional view of the structure of Fig. 11, on the line 12—12 thereof;

Fig. 13 is a view similar to Fig. 12, but showing the parts in locked position; and

20 Fig. 14 is a view, similar to Fig. 12, but showing a further modified form of structure.

Referring more specifically to the drawings, and first to the structural embodiment illustrated in Figs. 1-5, the structure shown comprises a

25 control mechanism, generally indicated by the numeral 10, adapted to effect the actuation of a controlled device or member 12 through the intermediary of a flexible control cable, generally indicated by the numeral 14. More specifically, the control cable comprises a composite shiftable structure, comprising a core wire 16 and an embracing wire coil 18, shiftable as a unit within a sheath coil 20. The shiftable control structures, comprising the parts 16 and 18, are connected

30 at one end to the controlled device in the form of the bell-crank lever 12, these parts being connected at their other end to the control mechanism 10 in a manner so as to be longitudinally reciprocable through a predetermined range of travel, or releasably locked from movement, as

35 may be desired.

The above described flexible transmission cable and operated device set forth one illustrative use of the control mechanism, presently to be described. It is to be understood, however, that the control mechanism of the invention may be employed in any suitable control installation, requiring shiftable movement within a predetermined range of travel, coupled with the releasable

40 locking of the operated parts in any selected position, as may be desired.

45 As best shown in Fig. 2, the control mechanism in the embodiment shown comprises a frame sleeve 22 adapted to be fixed to a panel or other suitable support 24, by means of a pair of nuts

26 and 28 screw threaded onto the end of the frame sleeve. The panel 24 may, for example, be the dashboard of a vehicle or the like on which the control installation is carried. The end of the sleeve 22, remote from the panel board, is suitably secured to the fixed sheath coil 20 of the flexible cable transmission by means of a collar or pressed fitting 30.

Slidable within the frame sleeve is an operating member in the form of an elongated sleeve 32. One end of this operating sleeve is suitably secured, as by means of swedging or the like, to the end of the shiftable coil 18 of the transmission cable, the arrangement thus being such that upon longitudinal shifting of the operating sleeve 32 within the frame sleeve 22, longitudinal reciprocal movements are imparted to the cable parts 16-18, whereby to effect the movement or operation of the controlled bell-crank member 12.

The opposite end of the operating sleeve 32 has swivelled engagement with the hub portion 34 of a control handle 36. Any suitable swivelled connecting means may be provided, a screw threaded connection being conveniently employed, as shown. It will be noted that the end of the sleeve 32 is not completely seated into the threaded socket within the control handle hub portion, an end space being provided as indicated at 38, so that the control handle may be rotated, for a purpose later to be described, without imparting corresponding rotation to the operating sleeve. However, the threaded connection insures that longitudinal movements imparted to the control handle will be correspondingly transmitted to the operating sleeve and associated transmission cable structure. In order to prevent rotative movements of the operating sleeve 32, the frame sleeve is provided with a suitable inwardly struck lug or detent, as indicated at 40, this lug projecting into a longitudinal slot or spline 42 provided in the operating sleeve member.

A control shaft 44 is disposed within the operating sleeve, for rotative movements therein, and for longitudinal shifting therewith. One end of this shaft is received into the hub portion of the control handle, and is suitably fixed therein as by means of a pin 46. The other end of the control shaft is formed on its end with a cam member or projection 48, as perhaps best shown in Fig. 5. The projection 48, in the particular embodiment shown, is circular, but is eccentrically positioned in respect to the axis of rotation of the control member, so that as the control member is rotated, the cam member 48 will be shifted in an orbital path or circumferentially within the sleeve 32. The normal or unlocked position of the cam projection 48 is illustrated in Fig. 3. The locking position of the projection is illustrated in Fig. 4.

The cam projection 48 cooperates with a holding element 50 in the form of a roller member, this roller member being loosely held within an opening 52 provided in the operating sleeve, and adapted to be thrust by the cam projection into engagement with the internal surface 54 of the fixed frame sleeve member.

When the parts are in unlocked position, as illustrated in Fig. 3, the roller member 50 is free from the surface of the frame sleeve, and lies loosely upon the operating cam or projection 48, as shown. Accordingly, with the parts in such condition, the operating sleeve 32 is freely shiftable within the frame sleeve, as indicated on an exaggerated scale by the space 56, Fig. 3. When

the locking cam 48 is rotated into locking position, by a predetermined rotary movement of the operating handle 36 (approximately 120° in the particular embodiment illustrated), as shown in Fig. 4, the holding or locking roller is thrust into engagement with the surface of the fixed frame sleeve, and this in turn forces the operating sleeve and frame sleeve into frictional engagement, for example as indicated at the point 58, thereby frictionally locking the operating sleeve to the frame sleeve, against longitudinal movement. The degree or magnitude of the locking action is dependent upon the degree of rotation and force imparted in turning the control handle, either a relatively light frictional resistance, or a substantially positive locking action being provided at the option of the operator depending upon the degree of turning movement and force imparted. When the parts are in locked position, as shown in Fig. 4, they are so proportioned so as to be self-holding, viz., the cam projection 48 and holding roller 50 are wedged into engagement so that they remain in engaged and locked position, after the operator releases his grip upon the control handle 36. As previously indicated, the spacing between certain of the parts is shown on an exaggerated scale in Figs. 3 and 4, so as to illustrate the locking action.

It will be seen that by reason of the construction provided, a readily made and easily fabricated structure is provided, which when released is smooth and free in operation, but which can be readily moved into locking position, to provide either a predetermined frictional resistance to movement or a positive locking action, holding the operating sleeve against longitudinal movement, as may be desired. The operating sleeve may be locked in position at any point within its range of travel. When once locked it will remain in locked condition, notwithstanding vibration or the like to which control installations of the type shown are frequently subjected over extended periods of time.

Particular attention is directed to the function of the sleeve 32, in insuring an invariable and reliable locking action. More particularly, the sleeve 32, while longitudinally shiftable, is constantly held in a predetermined angular position, and against rotation, by means of the spline connection 40-42. Inasmuch as the holding element 50 is mounted within the opening 52 of the operating sleeve, the holding element is likewise constrained against circumferential shifting in respect to the internal surface of the fixed frame sleeve. Accordingly as the control shaft 44 is rotated, resulting in the circumferential displacement of the cam projection 48 into locking position, it is insured that the desired locking action will take place in direct proportion to the degree of rotation imparted to the control handle. More particularly, the locking roller 50 is not permitted to slip circumferentially of the frame sleeve, as the cam projection 48 is moved, such as might otherwise occur due to vibration, dirt, or an inverted condition of the structure, as may result for example in an aircraft installation. A positive and reliable locking action is insured at all times and under all conditions of operation. The control handle 36, being firmly fixed to the control shaft 44, provides a positive operator therefor. The screw threaded connection between the control handle and the operating sleeve 32 insures that the operating sleeve will be properly longitudinally shifted as the control handle is actuated in a longitudinal direction, while at

the same time permitting the control handle to be rotated to effect the locking action, without imparting corresponding rotary movement to the operating sleeve. Inasmuch as the operating sleeve does not rotate, a swivel connection or the like between the operating sleeve and the flexible transmission cable or other device to be operated, is not required.

In the embodiment illustrated in Figs. 1-5, heretofore described, a locking action is imparted upon a predetermined rotation of the control handle from its normal or unlocked position, in either rotational direction. In certain instances it may be desired to permit a locking rotational movement of the control handle only in one direction. Suitable arrangements for effecting this result are illustrated in Figs. 6 and 7. The structure illustrated in Fig. 6 is the same as that previously described, the parts being shown in unlocked position corresponding to Fig. 3, except that in this instance the cam projection, as indicated at 48a, is provided with a transversely extending pin 60; the arrangement thus being such that the cam projection can be rotated into locking position in only one direction, viz., counterclockwise in the structure shown.

In Fig. 7 the structure likewise is similar to that previously described, except that the cam projection as indicated at 48b is in this instance provided with a lip portion 62 performing the function of the pin 60, viz., precluding rotation of the cam projection into locking position in more than one direction of movement.

In Figs. 8, 9 and 10 a further structural embodiment is illustrated. In this instance the structure is also generally similar to that shown in Figs. 1-5, except that the internal surface of the frame sleeve is provided with a helical screw thread, providing a more positive locking action as in some instances may be desired; and the holding element or roller is of specifically different shape, viz., in the form of a ball.

More specifically, it will be seen that in this instance the internal bore of the frame sleeve 22c is enlarged in respect to the longitudinally reciprocable operating sleeve 32c received thereby, a helical spring as indicated at 64 being disposed internally of the frame sleeve and forming the sliding surface within which the operating sleeve is reciprocable. The spring member may be satisfactorily secured within the bore of the frame sleeve by copper plating the frame sleeve bore, and also copper plating the spring member. The spring member is then inserted into position, and the composite structure subjected to the heating action of a furnace in a hydrogen atmosphere, whereby to effect the brazing of the spring to the frame sleeve bore, forming them into an integral unit. When mounted in position, the spring member in effect forms an internal helical screw thread within the bore of the fixed frame sleeve.

The parts are shown in locked position in Figs. 8 and 9, and in released or unlocked position in Fig. 10. The holding roller is in the form of a ball 66 which is thrust, as the cam 48c is moved into locking position, between the fixed convolutions of the spring member 64 and into engagement with the internal surface 54c of the frame sleeve, whereby to lock the parts in position. The fixed convolutions of the helical spring provide positive abutments interengageable with the locking ball which, as stated, may in certain instances be desired to provide a more positive locking or holding action. When the parts are in unlocked or released position, as shown in Fig. 10,

the ball is retracted so that it is not engageable with the spring convolutions. Inasmuch as the ball is held by the opening in the non-rotatable operating sleeve, in a position vertically above the cam member, the action of gravity will insure that the ball does not engage the spring convolutions so long as the control mechanism remains in the upright position illustrated.

Also in the structure of Figs. 8-10, the control shaft 44c is extended beyond the operating cam, for example as indicated at 68, whereby to provide a further bearing surface for the control member within the operating sleeve.

In Figs. 11-13, a still further form of structure is illustrated, omitting the intermediate operating sleeve. In this instance the frame sleeve 22d is secured by means of the nuts 28d and 26d to the panel 24d, as in the embodiments previously described, the end of the frame sleeve being secured to the sheath coil 20 of the control cable. The operating means for the cable parts 16-18 in this instance comprises an operating member 70 longitudinally slideable and also rotatable within the frame sleeve, under control of a handle 72 pinned to the end of the operating member or shaft 70. A collar 74 is pinned to the shaft to limit its movement in one direction, to the right, as shown in Fig. 11. The end of the shaft is connected by means of a swivel connection to the control cable 16-18 through the intermediary of a ball 76 secured to the end of the shaft, and a fitting 78 swaged onto the end of the shiftable cable 18.

The combined operating and locking control shaft 70 is provided with a cam portion 80 operable to thrust a locking roller 82 into engagement with the internal surface of the fixed frame sleeve, when the shaft is moved from unlocked position as shown in Figs. 11 and 12 to locked position as shown in Fig. 13. The locking engagement between the cam and roller thrusts the roller into frictional engagement with the surface of the frame sleeve, and simultaneously thrusts the shaft 70 into engagement with the frame sleeve, to provide the locking action. The swivel connection between the shaft 70 and the control cable permits the rotational movements of the shaft without imparting corresponding rotational movement to the transmission cable structure. As will be clear, the control shaft 70 may be shifted to various longitudinal positions under actuation by the handle 72, to effect the actuation of the operated mechanism; or locked in any adjusted position upon a predetermined rotational movement of the control handle and shaft structure.

In Fig. 14 an embodiment is illustrated the same as that shown in Figs. 11, 12 and 13 except that in this instance the frame sleeve as indicated at 22e is provided with a cut away or trough portion 84 extending the length of the sleeve for receiving the locking roller as indicated at 82e. The parts are shown in unlocked position in Fig. 14, and it will be noted that the space between the locking roller 82e and the cam portion 80e of the locking control shaft is slightly less than the depth of the groove 84. Accordingly even when the parts are in unlocked position the locking roller cannot move out of the trough 84. The trough therefore holds the locking roller in position at all times, and as the cam portion 80e is moved into engagement with the locking roller, as the locking control shaft is rotated, a positive locking action is insured as in the case of the structure of Figs. 1-5, previously described.

It is obvious that various changes may be made in the specific embodiments set forth for purposes of illustration without departing from the spirit of the invention. The invention is accordingly not to be limited to the specific embodiments shown and described, but only as indicated in the following claims.

The invention is hereby claimed as follows:

1. A control mechanism comprising a frame member, an operating member longitudinally reciprocable with respect to the frame member and adapted to be connected to a device to be controlled, a control handle operatively connected to the operating member for effecting its actuation, and locking means including a freely mounted roll and a cooperative symmetrally formed cam surface for releasably locking the operating member from movement in respect to the frame member, said locking means being controlled by a rotary movement of said control handle.

2. A control mechanism comprising a frame member, an operating member longitudinally reciprocable with respect to the frame member and adapted to be connected to a device to be controlled, a control handle operatively connected to the operating member for effecting its actuation, and locking means including a freely mounted roll and a symmetrally formed cooperative cam surface for releasably locking the operating member from movement in respect to the frame member, said cam surface being moved in an orbital path by a rotary movement of said control handle to effect the actuation of the locking means.

3. A control mechanism comprising an elongated frame sleeve, an elongated operating member longitudinally reciprocable within the frame sleeve and adapted to be connected to a device to be controlled, a control handle operatively connected to the operating member for effecting its actuation, and locking means including a freely mounted roll and a symmetrally formed cooperative cam surface for releasably locking the operating member from movement in respect to the frame sleeve, said locking means being controlled by a rotary movement of said control handle.

4. A control mechanism comprising an elongated frame sleeve, an elongated operating member longitudinally reciprocable within the frame sleeve and adapted to be connected to a device to be controlled, a control handle operatively connected to the operating member for effecting its actuation, and locking means including a roll element and a symmetrally formed cooperative cam surface for releasably locking the operating member from movement in respect to the frame sleeve, said cam surface being moved in an orbital path by a rotary movement of said control handle to effect the actuation of the locking means.

5. A control mechanism comprising a frame member, an operating member longitudinally reciprocable with respect to the frame member and adapted to be connected to a device to be controlled, a control handle operatively connected to the operating member for effecting its actuation, and locking means including a freely mounted roll and a cooperative cam member for releasably locking the operating member from movement in respect to the frame member, said control handle being freely rotatable to move said cam member in an orbital path to effect the actuation of the locking means.

6. A control mechanism comprising an elongated frame sleeve, an elongated operating member longitudinally reciprocable within the frame

sleeve and adapted to be connected to a device to be controlled, a control handle operatively connected to the operating member for effecting its actuation, and locking means including a roll element and a cooperative cam member for releasably locking the operating member from movement in respect to the frame sleeve, said control handle being freely rotatable to move said cam member in an orbital path to effect the actuation of the locking means.

5 7. A control mechanism comprising a frame member, an operating member longitudinally reciprocable with respect to the frame member and adapted to be connected to a device to be controlled, a control handle operatively connected to the operating member for effecting its actuation, and locking means including a freely mounted roll and a symmetrally formed cooperative cam member for releasably locking the operating member from movement in respect to the frame member, said locking means being controlled by an orbital movement of said cam member, and means for holding the holding element from circumferential movement with the cam member.

20 8. A control mechanism comprising a frame member, an operating member longitudinally reciprocable with respect to the frame member and adapted to be connected to a device to be controlled, a control handle operatively connected to the operating member for effecting its actuation, and locking means including a freely mounted roll and a circularly formed cooperative cam surface for releasably locking the operating member from movement in respect to the frame member, said locking means being controlled by a rotary movement of said control handle, and means operable in all positions of adjustment of the operating member for holding the holding element in a predetermined radial position in respect to the axis of reciprocation of the operating member.

35 9. A control mechanism comprising an elongated frame sleeve, an elongated operating member longitudinally reciprocable within the frame sleeve and adapted to be connected to a device to be controlled, a control handle operatively connected to the operating member for effecting its actuation, and locking means including a roll element and a cooperative cam member for releasably locking the operating member from movement in respect to the frame sleeve, said control handle being freely rotatable to move said cam member in an orbital path to control the actuation of the locking means, and means for holding the roll element in a predetermined radial position in respect to the axis of reciprocation of the operating member.

45 10. A control mechanism comprising an elongated frame sleeve, a shiftable sleeve disposed within the frame sleeve and longitudinally movable therein, a freely rotatable control handle operatively connected to the shiftable sleeve for effecting its actuation, a control member disposed within the shiftable sleeve and movable relative thereto by a rotary movement of said control handle, and locking mechanism comprising a freely mounted roll and a symmetrally formed cooperative cam surface actuated by the relative movement between said shiftable sleeve and said control member.

60 11. A control mechanism comprising an elongated frame sleeve, a shiftable sleeve disposed within the frame sleeve and longitudinally movable therein, a freely rotatable control handle

operatively connected to the shiftable sleeve for effecting its actuation, a control member disposed within the shiftable sleeve and movable relative thereto by a rotary movement of said control handle, and locking mechanism actuated by the relative movement between said shiftable sleeve and said control member, said locking mechanism comprising a freely mounted locking element actuated by a symmetrically formed cooperative cam surface on the control member, said locking element being shiftable through an opening in the shiftable sleeve into engagement with the frame sleeve.

12. A control mechanism comprising an elongated frame sleeve, a sleeve disposed within the frame sleeve and longitudinally movable therein, means for holding the operating sleeve from rotary movement, a freely rotatable control handle operatively connected to the operating sleeve for effecting its actuation, a control member disposed within the operating sleeve, said control member also being operatively connected to the control handle and shiftable within the operating sleeve by a rotary movement of the control handle, and a freely mounted locking element operable through an opening in the shiftable sleeve by a symmetrically formed cam surface on the control member into engagement with the frame sleeve by the relative movement between the shiftable sleeve and the control member.

13. A control mechanism comprising an elongated frame sleeve, an operating sleeve disposed within the frame sleeve and longitudinally movable therein, said operating sleeve being adapted to be connected to a device to be controlled, means holding the operating sleeve from rotary movement, a control handle operatively connected to the operating sleeve for effecting its actuation,

5 a control member disposed within the operating sleeve, said control member also being operatively connected to the control handle, and locking mechanism operated by a rotary movement of the control handle for releasably locking the operating sleeve to the frame sleeve, said locking mechanism comprising an orbital circularly shaped cam formed on the control member and a locking roll shifted thereby through an opening in the operating sleeve into engagement with the frame sleeve.

10 14. A control mechanism as defined in claim 13, wherein the frame sleeve is provided with a series of longitudinally spaced abutments engageable by the locking roll to provide a positive locking action.

15 15. A control mechanism as defined in claim 13, wherein the frame sleeve is provided with a spring member forming a helical screw thread 20 engageable by the locking roll to provide a positive locking action.
